COMBUSTION CHAMBER WITH DIVERSE AIR PATHS AND VORTICES PRODUCING VANES THEREIN FOR JET PROPULSION OR GAS TURBINE POWER PLANTS

Edmund D. Brown, Manchester, Conn., assignor to United Aircraft Corporation, East Hartford, Conn., a corporation of Delaware

Application November 28, 1947, Serial No. 788,585

14 Claims. (Cl. 60—39.65)

1

This invention relates to combustion chambers particularly adapted for use in jet propulsion or gas turbine power plants, as, for example, the combustion chamber in which air is heated between the compressor and turbine.

The fuel and air in a combustion chamber must be mixed to such a degree as to support continuous combustion, and the burning should be completed before the mixture reaches the turbine inlet or in a ram jet before the mixture reaches the thrust nozzle. Unless the burning can be completed within the combustion chamber, it is necessary to lengthen the chamber so that the burning may be completed before the gas reaches the end of the chamber. The result is that the entire power plant becomes excessively large, especially for use in aircraft. A feature of this invention is the complete mixing of air and fuel in a combustion chamber by introducing vortices having their axes substantially parallel to the direction of the air flow in the chamber.

It is customary, in order to assure proper combustion, to mix primary air with the fuel in an optimum fuel to air ratio and by-passing any excessive air around the chamber in which the combustion takes place. After combustion is substantially completed, the secondary air is mixed with the gas resulting from combustion for reducing the temperature of the resulting mixture to a safe temperature for the turbine operation. A feature of the invention is an arrangement for forming trailing vortices substantially on the mutual boundary between the gas resulting from the combustion process and the other fluid to cause thorough mixing.

A feature of the invention is the use of vortices in the combustion chamber for mixing the fuel with the air and also a second set or sets of vortices for mixing the products of combustion with the secondary air. Another feature of the invention is the staggering of the second set of vortices so that they are located between the vortices of the first set.

Where the combustion chamber is of annular construction, a feature of the invention is an arrangement of the vanes which creates the vortices in such a manner that the vortices adjacent to the outer wall surface of the burner will have a rotation opposite to the vortices adjacent the inner wall of the chamber.

Other objects and advantages will be apparent from the specification and claims, and from the accompanying drawing which illustrates

what is now considered to be a preferred embodiment of the invention.

Fig. 1 is an elevation of a power plant in which the combustion chamber is incorporated.

Fig. 2 is an enlarged longitudinally sectional view through the combustion chamber of Fig. 1.

Fig. 3 is a transverse sectional view on line 3—3 through the burner of Fig. 2.

Fig. 4 is a longitudinally sectional view through a can type of combustion chamber.

Fig. 5 is a transverse sectional view on line 5—5 through the chamber of Fig. 4.

Fig. 6 is a view similar to Fig. 4 of a modification.

The invention is shown in connection with an aircraft power plant which includes an axial flow compressor 2 discharging gas into an annular burner 4 from which the hot gas resulting from combustion of fuel therein, is discharged past a turbine 6 and through a thrust nozzle 8. The rotors 10 and 12 of the compressor and turbine, respectively, are interconnected as by a shaft 14 so that the turbine drives the compressor. It will be understood that the particular construction of either the compressor or turbine is not important; for the purpose of this invention, it is sufficient to note that air under pressure, as from the compressor 2, is delivered to the inlet end 16 of the burner and that the products of combustion are discharged, as through the turbine nozzle 18, at the discharge end of the combustion chamber.

As best shown in Fig. 2, the combustion chamber consists of an outer duct 20 and an inner duct 22 forming the outer and inner walls of the annular combustion chamber 4. Within and spaced from the outer duct 20 is an outer shield 24 which, in conjunction with a similar shield 26 spaced from the inner duct 22, defines the annular passage 28 within which the primary air and fuel from a nozzle 30 are mixed and burned. As shown, each of the shields 24 and 26 extends to a point adjacent to nozzle 30 and may be provided at points slightly downstream from the nozzle with openings 32 through which the air enters the annular passage.

The shields 24 and 26 extend in general parallel to the ducts 20 and 22 but adjacent the upstream end gradually approach each other at the portion of the shields where the air inlet openings 32 are located to assure entry of sufficient primary air to support combustion.

Downstream from the last set of air inlet openings 32 and adjacent to the part of the shields 24 and 26 that are substantially parallel to each

other, the shields carry one or more rows of inwardly extending vanes 34 and 36 respectively with the inner ends of the vanes spaced from the shields of the duct and so located as to establish trailing vortices, the axes of which are substantially parallel to the direction of the flow of air through the combustion chamber. It will be understood that the vanes are preferably of airfoil shape in cross-section with the chordwise axis of the vane arranged at a substantial angle to the longitudinal axis of the combustion chamber thereby creating a considerable lift resulting in a series of strong tip vortices.

The outer row of vanes 34 may be arranged with the angle of attack reversed with respect to the inner row of vanes 36, or the opposite rows of vanes may be at the same angle of attack so that the resulting vortices will be opposite directions as shown in Fig. 3.

Downstream from the trailing ends of the shields 24 and 26, the ducts 20 and 22 have one or more sets of vanes 38 and 40 projecting into the combustion chamber and also preferably of airfoil shape in cross-section. The inner ends of the vanes are spaced from the walls of the combustion chamber and preferably substantially on the mutual boundary between the secondary air which passes around the outside of the shields 24 and 26 and the gas resulting from the combustion process which occurs in the annular passage 28. Thus the tip vortices created by vanes 38 and 40, which are so arranged as to create a considerable lift and thereby a series of trailing vortices, cause mixing of the secondary air with the combustion products. As in the case of the primary vanes the secondary vanes 38 and 40 may have opposite angles of attack so that the vortices are in opposite directions or may have similar angles of attack as shown in Fig. 3 so that the vortices resulting from the inner and outer vanes are in the same direction and thus are in opposition to each other. Preferably the secondary vanes 38 and 40 are spaced between the primary vanes 34 and 36, as best shown in Fig. 3, and also as shown, the outer primary vanes 34 and the outer secondary vanes 38 preferably have similar angles of attack, although it will be apparent that under certain circumstances the arrangement of these vanes at opposite angles of attack would be advantageous.

The invention is equally applicable to the round or can type of combustion chamber. As shown in Figs. 4 and 5, the combustion chamber instead of being annular in construction as above described, is round and a number of combustion chambers are arranged in a ring around the shaft of the power plant. In these figures the combustion chamber is in the form of a substantially circular duct 42 forming the wall of the combustion chamber and this duct has a substantially circular shell 44 within and spaced from the walls of the duct and forming the passage 46 within which the primary air and the fuel are burned. The shell 44 consists of a substantially conical portion 48, the inlet end of which substantially surrounds the fuel nozzle 50. The larger end of the conical section 48 which is the downstream end connects with a substantially cylindrical portion 52 preferably located within a part of the duct 42 which is also substantially cylindrical. The conical portion 48 has air passages 53 by which primary air enters the passage 46 to mix with fuel from nozzle 50.

To assure proper mixing, the shell 44 is provided adjacent the upstream end of its substan-

tially cylindrical portion with a number of inwardly extending vanes 54 preferably of air-foil shape in cross-section. The inner ends of these vanes are spaced from the shell and the vanes preferably have a substantial angle of attack with respect to the fluid flowing through the passage thereby creating considerable lift and causing strong tip vortices trailing downstream from the vanes to assure thorough mixing of the fuel and primary air.

After combustion is substantially completed, the combustion products from the passage 46 are caused to mix with the secondary air flowing around the shell by a second set of vanes 56 projecting inwardly from the duct 42 and with the inner ends of the vanes spaced radially from the duct wall and substantially in alignment with the shell so that the tips are located on the boundary between the secondary air and the products of combustion. These vanes also have a substantial angle of attack with respect to the fluid in the duct thereby creating strong tip vortices which will assure thorough mixing of the secondary air with the products of combustion.

As in the annular type of burner, the second set of vanes is preferably staggered with respect to the first set as shown in Fig. 5 and the angles of attack of the two sets of vanes are preferably the same so that the secondary vortices follow the primary vortices. It will be apparent that under certain conditions it will be advantageous to reverse the angle of attack of the second set of vanes thereby causing the secondary vortices to rotate in a direction opposite to that of the primary vortices.

With respect to Fig. 6 the combustion chamber may be so arranged that the vanes for mixing the secondary air with the products of combustion are located directly at the end of the passage in which combustion takes place. As shown, the combustion chamber is in the form of a substantially circular duct 58 forming the wall of the combustion chamber and surrounding a substantially circular shell 60 within and spaced from the walls of the duct. The shell forms the passage 62 within which the primary air and fuel are burned. The fuel may, for example, be delivered through a nozzle 64 to a cup 66 located adjacent to the inlet end of the passage 62. At the inlet end of the shell 60 are a series of vanes 68, extending inwardly from the shell, and with the inner ends of the vanes preferably in alignment with the brim of the cup so that the flow of air into the passage past the vanes 68 will create strong tip vortices which will be located substantially on the mutual boundary between the air entering the chamber and the fuel discharging from the cup. The leading edges of the vanes support the brim of the cup and the vanes extend downstream therefrom. The effective part of the vanes is thus beyond the end of the cup in the direction of gas flow.

The secondary air passes through the space between the shell 60 and the duct 58 to the downstream end of the shell 60 where a part of the secondary air enters the space in which combustion is taking place by flowing over a series of vanes 70, the leading edges of which are substantially in line with the end of the shell 60 and the inner ends of which are substantially coincident with the shell 60. These vanes 70 may be supported from the outer duct 58 by ribs 72 which also function to support a second shell 74 which extends downstream from the vanes 70 to an additional row of vanes 76.

This row of vanes extends between the duct 58 and the downstream end of the shell 74. The vanes 76 are arranged so that the inner ends thereof coincide substantially with the shell. These vanes may be arranged with the same angle of attack as the row of vanes 70 or they may be reversed as shown, since by reversal of the vanes, it is possible to create a greater turbulence. The effective part of the vanes 70 and 76 are located beyond the ends of the shields 60 and 74 respectively, in the direction of gas flow so that they may function to produce the tip vortices in the gas flowing over the vanes.

Although in the arrangements shown, all of the vanes of any one set are arranged with the same angle of attack, it will be apparent that adjacent vanes in any set may be arranged with opposite angles of attack, as it is found that such an arrangement produces more adequate mixing of the primary air and the fuel to thereby shortening the space within which the combustion takes place. The use of oppositely arranged vanes in improving the flow of fluid in a duct is claimed in the copending application of Bruynes, Serial No. 769,042, filed August 16, 1947, now Patent No. 2,558,816.

It is to be understood that the invention is not limited to the specific embodiment herein illustrated and described, but may be used in other ways without departure from its spirit as defined by the following claims.

I claim:

1. In a combustion chamber, a duct forming the wall of the chamber, a shell within said duct and forming a passage within which the primary air and fuel are mixed and burned, the secondary air flowing around said shell, means for creating vortices within said shell at points spaced from the wall thereof to mix the fuel and air with the centerline of the vortices substantially parallel to the axis of the duct, and other means spaced from and beyond the discharge end of said shell for creating additional vortices for mixing the fluid from the shell with the secondary air with the centerlines of the vortices substantially parallel to the axis of the duct.

2. In a combustion chamber, a duct forming the wall of the chamber, a shell within said duct and forming a passage within which the primary air and fuel are mixed and burned, the secondary air flowing around said shell, means for creating vortices in said shell at points spaced from the wall thereof to mix the fuel and air, and other means spaced from and beyond the discharge end of said shell for creating additional vortices for mixing the fluid from the shell with the secondary air, said other means being arranged to produce vortices having the same direction of rotation as the first vortices.

3. In a combustion chamber, a duct forming the wall of the chamber, a shell within said duct and forming a passage within which the primary air and fuel are mixed and burned, the secondary air flowing around said shell, means for creating vortices in said shell at points spaced from the wall thereof to mix the fuel and air, and other means spaced from and beyond the discharge end of said shell for creating additional vortices for mixing the fluid from the shell with the secondary air, said other means being arranged to produce vortices having the opposite direction of rotation to that of the first vortices.

4. In a combustion chamber, a duct forming the wall of the chamber, a shell within said duct and forming a passage within which the primary air and fuel are mixed and burned, the

secondary air flowing around said shell, and vanes extending into said chamber, with one end of each vane spaced from the wall thereof, the vanes being arranged at an angle to the flow of fluid through said duct so that the ends thereof will create vortices for mixing the fuel and air in the chamber, and other vanes positioned in said duct beyond the discharge end of the shell and arranged at an angle to the flow for creating additional vortices, the free ends of said other vanes being substantially in line with the shell so that the vortices will have their axis substantially in line with the shell.

5. In a combustion chamber, a duct forming the wall of the chamber, a shell within said duct and forming a passage within which the primary air and fuel are mixed and burned, the secondary air flowing around said shell, and vanes extending into said chamber, one end of each vane being spaced from the wall thereof, the vanes being arranged at an angle to the flow of fluid through said duct so that the ends thereof will create vortices for mixing the fuel and air in the chamber, and other vanes positioned in said duct beyond the discharge end of the shell and arranged at an angle to the flow for creating additional vortices, with the first set of vanes in alignment with the second set of vanes.

6. In a combustion chamber, a duct forming the wall of the chamber, a shell within said duct and forming a passage within which the primary air and fuel are mixed and burned, the secondary air flowing around said shell and vanes extending into said chamber, one end of each vane being spaced from the wall thereof, the vanes being arranged at an angle to the flow of fluid through said duct so that the ends thereof will create vortices for mixing the fuel and air in the chamber, and other vanes positioned in said duct beyond the discharge end of the shell and arranged at an angle to the flow for creating additional vortices, with both sets of vanes having approximately the same angular arrangement in relation to the direction of flow.

7. In an annular combustion chamber, inner and outer ducts forming the inner and outer walls of the annular chamber, inner and outer shields within said chamber and spaced from said ducts to define, between said shields, an annular passage within which the primary air and fuel are mixed and burned, and a number of vanes positioned within the passage with one end of each of the vanes spaced from the shields and arranged to cause trailing vortices to improve the mixing of air and fuel.

8. In an annular combustion chamber, inner and outer shields between which is defined an annular passage and wherein which the primary air and fuel are mixed and burned, and a number of vanes positioned within the passage with one end of each of the vanes spaced from the shields to cause trailing vortices to form as the fluid flows through the passage.

9. In an annular combustion chamber, inner and outer ducts forming the inner and outer walls of the annular chamber, inner and outer shields within said chamber and spaced from said ducts to define, between said shields, an annular passage within which the primary air and fuel are mixed and burned, and a number of vanes extending into said passage from one of said walls with one end of each of the vanes spaced from the shields to cause trailing vortices to improve the mixing of air and fuel.

10. In an annular combustion chamber, inner

and outer ducts forming the inner and outer walls of the annular chamber, inner and outer shields within said chamber and spaced from said ducts to define, between said shields, an annular passage within which the primary air and fuel are mixed and burned, and a number of vanes extending into said passage from each of said walls, with one end of each of the vanes spaced from the shields to cause trailing vortices to improve the mixing of air and fuel.

11. In an annular combustion chamber, inner and outer ducts forming the inner and outer walls of the annular chamber, inner and outer shields within said chamber and spaced from said ducts to define, between said shields, an annular passage within which the primary air and fuel are mixed and burned, and a number of vanes extending into said passage from each of said walls, with the vanes on one wall arranged at an angle opposite to the vanes on the other wall.

12. In an annular combustion chamber, inner and outer ducts forming the inner and outer walls of the annular chamber, inner and outer shields within said chamber and spaced from said ducts to define, between said shields, an annular passage within which the primary air and fuel are mixed and burned, and a number of vanes extending into said passage from one of said walls with one end of each of the vanes spaced from the shields to cause trailing vortices to improve the mixing of air and fuel, and additional vanes extending into the chamber beyond the ends of the shields to cause mixing of the fluid in the passage with the secondary air in the space between either shield and the adjacent duct.

13. In a combustion chamber, a duct forming

the wall of the chamber, a shell within said duct and forming a passage within which the primary air and fuel are mixed and burned, the secondary air flowing around said shell, means for creating tip vortices in said shell adjacent the inlet end at points spaced from the wall thereof to mix the fuel and air, and other means in the form of vanes at the discharge end of said shell for creating additional vortices, the last vortices being formed with their axes substantially coincident with the shell.

14. In a combustion chamber, a duct forming the wall of the chamber, a shell within said duct and forming a passage within which the primary air and fuel are mixed and burned, the secondary air flowing around said shell, means for creating tip vortices in said shell adjacent the inlet end at points spaced from the wall thereof to mix the fuel and air, a second means at the discharge end of said shell for creating vortices with their axes substantially coincident with the shell, and vanes spaced downstream from said second means for causing additional tip vortices.
